UNITED STATES PATENT OFFICE

VICTORIA M. BONARDI, OF WORCESTER, MASSACHUSETTS, ASSIGNOR TO GABRIELE MAURIELLO, OF WORCESTER, MASSACHUSETTS

DESIGN FOR A SANDWICH

Application filed August 28, 1930. Serial No. 36,814. Term of patent 7 years.

To all whom it may concern:

Be it known that I, VICTORIA M. BONARDI, a citizen of the United States, residing at Worcester, in the county of Worcester, and State of Massachusetts, have invented a new, original, and ornamental Design for a Sandwich, of which the following is a specification, reference being had to the accompanying drawing, forming part thereof.

Fig. 1 is a plan of a sandwich, and Fig. 2 is an edge view, showing my new design.

The reverse side of the sandwich can be identical with that shown or plain.

I claim:

The ornamental design for a sandwich as shown and described.

VICTORIA M. BONARDI.
